DISTRIBUTION SYSTEM FOR SHOE
FACTORIES

Myron O. Frost, Richmond Heights, and Peter Mattler, St. Louis, Mo., assignors, by mesne assignments, to The Lamson Company, Syracuse, N. Y., a corporation of Massachusetts

Original application June 20, 1932, Serial No. 618,251. Divided and this application November 16, 1932, Serial No. 642,916

8 Claims. (Cl. 214—11)

This invention relates to distribution systems for shoe factories and with regard to certain more specific features, to selective distribution systems for such factories.

5 This invention is a division of the invention set forth in our patent application, Serial Number 618,251, filed June 20, 1932, patented April 10, 1934, No. 1,954,124 for Distribution system for shoe factories.

10 Among the several objects of the invention may be noted the provision of a selective distribution system for shoe factories wherein different units of work or bundles of elements may be made up and placed upon a conveyor for distribution to selected points; the provision of apparatus of the class described wherein a given operator may determine the manner of distribution according to the requirements of other operators or according to other variables; the provision of apparatus 15 of the class described which shall be operative upon individual pieces of aggregates of a number of pieces; and the provision of improved apparatus for carrying out the above ends. Other objects will be in part obvious and in part pointed 20 out hereinafter.

25 The invention accordingly comprises the elements and combinations of elements, features of construction, and arrangements of parts which will be exemplified in the structures hereinafter described, and the scope of the application of which will be indicated in the following claims.

30 In the accompanying drawings, in which is illustrated one of various possible embodiments of the invention,

35 Fig. 1 is a side elevation of the invention;

Fig. 2 is a plan view of certain clutch elements of Fig. 1, the view being taken substantially along line 2—2 of Fig. 1;

40 Fig. 3 is an enlarged front elevation of certain operating controls;

Fig. 4 is a front elevation of Fig. 2;

Fig. 5 is a cross section taken on line 5—5 of Fig. 1; and,

45 Fig. 6 is an end elevation taken from the right of Fig. 4.

Similar reference characters indicate corresponding parts throughout the several views of the drawings.

50 Referring now more particularly to Fig. 1, there is shown at numeral 1 a table along which shoe operators are seated at stations such as at points X, for example, said operators performing with or without machines or the like, operations in connection with the manufacture of shoes, such as for 55 example, the assembling of various pieces to form

uppers, liners or the like. The operators require to have material distributed to them and it is the purpose of this invention to effectively and efficiently make such a distribution.

5 A frame 161 is arranged adjacent to receiving stations X and a distributing station Y, it being intended that the operator at Y shall assemble various bundles of material for shoes and predeterminedly distribute them to those who are to work thereon at stations X. The stations X are 10 provided with receiving racks 163, into which said bundles are to be dropped.

Sprockets 165, 165' are rotatably mounted to carry an endless chain 167 as shown in Fig. 1. The lower, right-hand sprocket 165' (Fig. 1) is 15 driven from a speed reducer 169 (see also Figs. 2, 4, and 6), said speed reducer being energized from the driven side 172 of a clutch 171. The driving side 170 of said clutch 171 is energized by a belt 173 from a motor 175. 20

It is the intention to have the clutch 171 manually closable, the period of closing being automatically regulated to provide a predetermined angular movement of the lower right-hand driving sprocket 165' (Fig. 1). In the present example, the angular movement of said sprocket 25 is to be 360°.

In order to accomplish the above action of the clutch 171, there is provided a bell crank lever 177, which, by means of a spring 179 which reacts 30 against the head of a bolt 181, is normally pressed clockwise (Fig. 4) to press the driving side 170 of the clutch 171 into closed position against the driven element of said clutch. However, this bell crank lever 177 is normally prevented from so 35 closing the clutch 171 by an adjustable link 185 having a lost-motion engagement 187 with an extension 189 of the bell crank lever 177.

The link 185 is articulated with a bell crank lever 191, which by means of a stronger spring 193, 40 is normally pressed in a counter-clockwise direction. The result is that under the influence of the stronger spring 193 overcoming the influence of the weaker spring 179, the bell crank lever 177 is pressed counterclockwise to normally prevent closing of the clutch.

To manually close the clutch, there is provided an operator's foot pedal 195 connected by means of link 197 to a rocker arm 199, the latter having a pin 201 for engagement with one arm of the 50 bell crank lever 191. It is clear that temporary depression of the foot pedal 195 will result in withdrawing of the link 185 to the right and thereby causing the spring 179 to press the bell crank lever 177 into engagement with the driving mem- 55

ber 170 of the clutch 171, thereby closing the clutch and causing the speed reducer 169 to effect rotation of the driving sprocket 165.

The period of motion of said sprocket is controlled by a cam 203 fastened to the drive shaft 205 of said sprocket 165. This cam 203 has a notch 207 in which a pawl 209 may be positioned, the clutch under these conditions (Fig. 4) being forced open due to the action of spring 193 on the mechanism 191, 185, 189, 177. The pawl 209 is fixed with respect to the bell crank lever 191. When the pedal 195 is depressed temporarily to close the clutch 171, the pawl 209 is thrown out of engagement with the notch 207, thus closing the clutch 171 through action of spring 179 to drive the shaft 205 clockwise.

After driving of the shaft 205 is once started, the pawl 209 rests on the high portion 206 of the cam 203 and does not permit opening of the clutch for approximately 360°. At this time the operator's foot may be taken from the pedal 195. The motion of the cam 203 is counterclockwise as shown by the arrow in Fig. 4, and when the notch 207 is again engaged by the pawl 209, said notch permits the pawl 209 to move to the left to cause opening of the clutch under action of the spring 193.

In order that inertia shall not carry on beyond the point at which it is desired to stop, there is provided a brake shoe 211 adjustable by means of a set screw 213 on the bell crank lever 177. When the bell crank 177 is rotated to the left, as when opening the clutch 171, the shoe 211 is caused to contact with the periphery 35 of said clutch 171 to brake the movement thereof.

Spaced along the chain 167 are holding clamps 215, the same being spaced distances apart equal to the pitch line distance traversed in one revolution by a point on the pitch line of the driving sprocket 165; that is to say, upon temporary depression of the pedal 195 and a consequent predetermined movement of the driving sprocket 165, the chain 167 will move so as to cause a given posterior clamp 215 to be replaced by an anterior clamp.

Each clamp comprises an extension 217 on which is pivoted a jaw 219 normally spring pressed by a spring 221 to press against the respective extension 217, said jaw 219 having a tail piece 223 normally in the position shown in Fig. 6, in which the clamp is closed. This tail piece 223 is adapted to be actuated to open the clamp when a bundle is to be dropped or when applying a bundle, the clamp being closed during carriage of the same.

The bundle is loaded at the station Y and at this point there is provided a framework 225 on which is pivotally supported a platen 227 having the sloping lip portion 229. The platen may be elevated or permitted to be depressed by gravity by means of a pin 231 resting upon a bell crank 233, the latter being operated by means of a rod 235 reaching from an extension 237 of said rocker 199.

Thus it will be seen that upon depression of said pedal 195, the platen 227 is raised. When the platen is raised, it contacts with the tail 223 of the clamp 215 which happens to be in position over the platen, thereby opening the clamp 215 (in Fig. 6 it is shown closed), thereby permitting application to the clamp of a bundle to be carried. Then, when the foot is released from the pedal 195, (the clutch 171 continuing to be closed for the period stated) the platen 227 drops, thereby causing the clamp 215 to close

and support the respective bundle to transport the same. The described movability of the platen avoids the necessity for the operator waiting until the clamp has moved away from the platen before closure. The respective clamp closes at the operator's desire, merely by taking the foot from the pedal 195. Thus it may be said that depression of the pedal initiates movement of the clamps and release of the pedal initiates clamp closure before a clamp would otherwise move from over the platen. As the clutch continues to drive for the predetermined period, the clamp 215 in question moves away from the platen 227 and when the pedal 195 is again operated, the clamp 215 is not effected but continues to carry 15 the bundle along the path of the chain 167. The movement is intermittent. If the operator happens to raise the platen 227 before the arrival of a clamp, the tail of the clamp rides upon a downwardly bent lip 229 and automatically 20 opens instead of improperly interfering.

In order to automatically drop the bundles at predetermined stations X, there are provided knock-off levers 239 of the bell crank type adjacent the respective stations, normally set at the 25 dotted line positions shown in Fig. 3, this being by means of a spring 241 reacting from a fixed arm 243. The end 245 of each bell crank lever 239 is adapted, when said bell crank is drawn to full line position (Fig. 3), to contact with the 30 tail piece 223 of any clamp 215 which is in position for delivery of its load.

In order to provide a reaction when said end 245 is moved up, there is provided a fixed runner 247 against which the upper extension 217 of the 35 clamp 215 reacts (Fig. 5) so that when the bell crank 239 is moved counter-clockwise, the clamp 215 is opened as shown in Fig. 5. Thus, the clamp is caused to drop its load.

The various knock-out mechanisms are adapted to be individually and manually controlled by the operator at Y, this being done by means of tension members 249 attached to the bell crank levers 239 by springs 251. The other ends of said tension members 249 are, by means of bell crank 45 levers 253, articulated to rods 255 operable by hand levers 257 under control of the distributing operator (see Fig. 6). The hand levers 257 pass through a control plate 259 having L-shaped slots 261 therein, the latter permitting vertical 50 movement of the hand levers 257 and permitting the operator to hold said levers in their lowermost positions by notching them into the lower limbs of the L-shaped openings 261.

In Fig. 2 the right-hand lever 257 is shown 55 notched down and the left-hand lever is shown up. The lever 257 which is notched down holds said respective bell crank 239 in the full-line position to press open the respective clamp 215 so that said clamp drops its bundle into the respective receptacle 163. If the stations X are provided with numerals to designate the same, the distributing operator at Y has corresponding designating numerals on the plate 259 as shown in Figs. 1 and 2.

In order that the chain 167 may be supported without interfering with the action of the clamps 215, the extensions 217 from the chain 167 have flat portions 263 engageable with stationary supporting runners 265, said runners 265 clearing the 70 tail piece 223, (see Figs. 1 and 5).

The operation of the invention is as follows:

The distributing operator at Y makes up the bundles of material according to order or discretion. A given bundle is then taken, and as the 75

pedal 195 is temporarily depressed so as to open the respective clamp 215 over the platen 227, the bundle is applied to said respective clamp 215 and the pedal 195 is released. The release of this 5 pedal causes closing of the respective clamp 215 so that it holds the bundle. If the platen is raised too early, the lip 229 will prevent interference.

The said depression of the pedal 195 has started the chain 167, due to the temporary closing 10 of the clutch 171. The clutch 171 remains closed after the pedal 195 is released until the cam 203 has rotated once under the pawl 209. After one 15 revolution, the pawl 209 moves quickly to the left in the notch 207, thereby causing opening of the clutch and braking by means of the brake 211. Thus, motion of the chain 167 is stopped with a new clamp 215 in place above the platen 227.

The stations X are in full view of the distributing operator at station Y, so that said operator at station Y can determine what operators at station X are out of work and/or what they are working upon. The operator at station Y therefore controls the levers 257 so as to set a 20 releasing mechanism at a predetermined station so that it shall cause opening of the clamps 215 as said clamps pass. This opening causes the bundles to be dropped into the respective receiving racks 164. When the operator at station Y 25 sees that the predetermined operator at X has enough work, she raises the respective lever and depresses another so that another selected operator begins to receive work. Thus the operators at stations X can be readily supplied with 30 work at all times.

The bundles pass from the operator at Y to the operators at X by way of the upper reach of the chain and thus consume time which is advantageous in effecting drying, setting or the like of adhesive and the like on the pieces constituting the bundles. The definite intermittent movement instead of a continuous movement is also conducive to complete drying.

The distributing operator at station Y has one 45 of the levers 257 depressed at all times so as to prevent the return of work to said operator at Y and cause said work to drop off at one of said stations X.

In view of the above, it will be seen that the 50 several objects of the invention are achieved and other advantageous results attained.

As many changes could be made in carrying out the above constructions without departing 55 from the scope of the invention, it is intended that all matter contained in the above description or shown in the accompanying drawings shall be interpreted as illustrative and not in a limiting sense.

60 We claim:

1. In shoe machinery, a conveyor having in 65 respect to a loading station, an outwardly moving reach and a return reach, unloading stations located on the return reach, clamps conveyed by the conveyor and adapted to support material, a mechanism for driving the conveyor, an automatically opening clutch in said mechanism, a movable platen having opening and closing positions with respect to the clamps, operating means whereby said operator simultaneously closes the clutch and positions said platen for 70 opening a clamp, each action of said clutch resulting in predetermined movement of said clamps, the clamps being spaced so that during said movement an anterior clamp is progressed

into the former position adjacent the platen of a posterior clamp.

2. In shoe machinery, a movable conveyor having with respect to a loading station an outwardly moving reach and a return reach, normally closed clamps conveyed by the conveyor and adapted to support material, a mechanism for driving the conveyor, an automatically opening clutch in said mechanism manually closable by an operator permitting a substantially long period of carriage to a first unloading station, a movable platen having opening and closing positions with respect to the clamps, operating means whereby said operator simultaneously closes the clutch and positions said platen for opening a clamp, each manual closing of said clutch resulting in predetermined movement of said clamp due to automatic operation of the clutch, the clamps being spaced so that during said movement an anterior clamp is progressed into the former position adjacent the platen of a posterior clamp.

3. In shoe machinery, a conveyor having with respect to a loading station a substantial length of outwardly moving reach and a return reach, receiving operator stations located along the conveyor, clamps conveyed by the conveyor and adapted to support material, a mechanism for driving the conveyor, an automatically opening clutch in said mechanism, a movable platen having opening and closing positions with respect to the clamps, operating means whereby said operator may close the clutch and position said platen for opening a clamp, each operation of said clutch resulting in temporary movement of 35 the clamps, the clamps being spaced so that during said movement an anterior clamp is progressed into the former position adjacent the platen of a posterior clamp, clamp-opening mechanisms respectively juxtaposed near the respective unloading stations, and controls for said clamp opening mechanisms, said controls being operable by an operator at the loading station.

4. In shoe machinery, a conveyor served by a loading station and serving unloading stations, 45 clamps conveyed by the conveyor and adapted to support material, a mechanism for driving the conveyor, a manually closing and automatically opening clutch in said mechanism, a movable platen having opening and closing positions with 50 respect to the clamps, operating means whereby a loading operator may close the clutch and position said platen to open a clamp, each operation of said clutch resulting in temporary movement of said clamps, the clamps being spaced so 55 that during said movement an anterior clamp is progressed into the position near the platen of a posterior clamp.

5. In shoe machinery, a conveyor served by a loading station and serving unloading stations, 60 clamps conveyed by the conveyor and adapted to support material, a mechanism for driving the conveyor, a manually closing and automatically opening clutch in said mechanism, a movable elongated platen having opening and closing positions with respect to the clamps, operating means whereby a loading operator may close the clutch and position said platen to open a clamp, each operation of said clutch resulting in temporary movement of said clamps, the clamps being 65 spaced so that during said movement an anterior clamp is progressed into the position near the platen of a posterior clamp, said platen being formed with a curved leading edge and adapted to cause opening of approaching clamps when 70 75

the platen is in its opening position, the curved edge and elongated features avoiding interference with clamps and permitting variation in clamp travel, respectively.

- 5 6. In shoe machinery, a conveyor having with respect to a sending operator station an outwardly moving reach and a return reach, receiving operator stations being located along the conveyor, clamps conveyed by the conveyor and adapted to support material, a movable platen having opening and closing positions with respect to the clamps, an operating linkage whereby said operator may position said platen for opening a clamp and reposition the same for closing the clamp, whereby the operator may load the clamps at will, and driving mechanism for the conveyor including a clutch adapted to open automatically upon completion of a predetermined movement after the manual closure thereof by the operator.
- 10 7. In shoe machinery, a conveyor, means for supporting articles on the conveyor at spaced points, a driving mechanism for the conveyor, a clutch adapted to be manually closed by temporary action of an operator and to automatically open after a predetermined movement, control means whereby the operator may operate the clutch said clutch controlling said driving mech-
- 15 20 25

anism to move the conveyor a distance equal to the spacing between the points of support of said articles, and mechanism adapted to prepare the article supporting means to receive articles operable by the operator independently of the period of clutch operation but operable from said clutch operating control.

8. In shoe machinery, a conveyor, means for supporting articles on the conveyor at spaced points, a driving mechanism for the conveyor, a clutch adapted to be manually closed by temporary action of an operator and to automatically open after a predetermined movement, control means whereby the operator may operate the clutch said clutch controlling said driving mechanism to move the conveyor a distance equal to the spacing between the points of support of said articles, mechanism adapted to prepare the article supporting means to receive articles operable by the operator independently of the period of clutch operation but operable from said clutch operating control, and drop mechanisms at unloading points selectively operable by said operator from a point other than said clutch operating control.

25
